UNITED STATES PATENT OFFICE.

TANDY B. THURMAN, OF ENID, OKLAHOMA.

FOLDING BED.

1,199,442.

Specification of Letters Patent. Patented Sept. 26, 1916.

Application filed September 27, 1915. Serial No. 52,903.

To all whom it may concern:

Be it known that I, TANDY B. THURMAN, a citizen of the United States, residing at Enid, in the county of Garfield and State 5 of Oklahoma, have invented certain new and useful Improvements in Folding Beds, of which the following is a specification, reference being had to the accompanying drawings.

10 This invention relates to certain improvements in folding beds and has relation more particularly to a device of this general character of the well known davenport type; and it is an object of the invention to provide a device of this general character with 15 novel and improved means whereby the swinging front and hinged back may be effectively supported in a position to permit the device to be employed as a bed, and 20 whereby the swinging front and hinged back may be readily adjusted into folded relation.

The invention consists in the details of construction and in the combination and 25 arrangement of the several parts of my improved folding bed whereby certain important advantages are attained and the device is rendered simpler, less expensive and otherwise more convenient and advantageous 30 for use, all as will be hereinafter more fully set forth.

The novel features of the invention will be carefully defined in the appended claim.

In order that my invention may be the 35 better understood, I will now proceed to describe the same with reference to the accompanying drawings, wherein—

Figure 1 is a view, partly in elevation and partly in section, illustrating a bed structure 40 with an embodiment of my invention applied thereto; Fig. 2 is a fragmentary view in top plan of the device as disclosed in Fig. 1; Fig. 3 is a view similar to Fig. 1 with the swinging front and hinged back in folded 45 adjustments; Fig. 4 is a view in perspective, detached, of the controlling member for the swinging front as herein embodied; and Fig. 5 is a view in perspective, detached, 50 of one of the guides for the controlling member as herein employed.

As disclosed in the accompanying drawings, 1 denotes the seat or fixed section of a davenport or the like supported in any desired manner. Detailed description of the 55 supporting mechanism as illustrated in the accompanying drawings is purposely omit-

ted as the same is to be embodied in a separate application and wherein the structure of said supporting means will be more specifically disclosed and particularly claimed. 60 The present drawings illustrate only one end portion of the davenport or bed as the opposite end is to be arranged in accordance with the present disclosure.

Hingedly engaged with the seat or fixed section 1 is the back 2 disposed longitudinally of the seat or fixed section 1 and adapted to swing upwardly and in pivotal engagement with the opposite longitudinal margin of the seat or fixed section 1 is the 65 swinging front 3. The particular construction of the seat or fixed section 1, the back 2 and the swinging front 3 forms no part of my present invention, except that it is preferred that the end members thereof be 70 formed of angle iron.

As herein disclosed, each of the end members 4 of the back section 2 is provided with an extension 5 of predetermined length and having pivotally engaged with the free extremity thereof, as at 6, the rigid link 7 of predetermined length and disposed transversely of the seat or fixed section 1 and positioned therebeneath, the inner end of said link 7 being pivotally engaged, as at 8, with 80 the elongated controlling member 9 slidably engaged with the adjacent end member 10 of the seat or fixed section 1 through the medium of the guides 11, the construction of which being more particularly disclosed 85 in detailed Fig. 5.

It will be noted that as the hinged back is swung downwardly the controlling member 9 will be forced outwardly and vice versa, and when the controlling member 9 is in its outer adjustment, as particularly disclosed in Fig. 1, it is adapted to underlie a side member 12 of the swinging front 3 whereby it will be perceived that said swinging front 3 is effectively maintained in a 95 horizontal or extended position so that the davenport may be effectively used as a bed. The member 9 travels in a path occupying the horizontal plane in which is located the pivotal connection between the seat or fixed section 1 and the swinging front 3. It is to 100 be understood that the swinging front 3 is manually swung upwardly. When the hinged back 2 is swung upwardly the controlling member 9 will be retracted from beneath the swinging front 3 whereupon said swinging front 3 will automatically drop 105 110

and in order to limit the downward movement of the swinging front 3, I find it of advantage to provide the forward end of the operating member 9 with the depending extension 14 substantially perpendicular to the member 9 and serving as a stop for the swinging front 3, as is believed to be clearly shown in Fig. 3 of the accompanying drawings. It is also to be noted that the weight 10 of the swinging front 3 when in lowered position will, by the contact of said front 3 with the depending extension 14 on the operating member 9, serve to maintain the back section 2 substantially rigid in its elevated position. It is also to be noted that the inward movement of the operating member 9 under the influence of the hinged back 4 is such as to offer no obstruction to the downward movement of the swinging front 15 3. It is also to be observed that the upward movement of the hinged back 2 is limited by contact of the end members 4 with the end members 10 of the seat or fixed section 1.

From the foregoing description, it is 20 thought to be obvious that a folding bed constructed in accordance with my invention is of an extremely simple and comparatively inexpensive nature and is particularly well adapted for use by reason of the 25 convenience and facility with which it may be assembled, and it will also be obvious that my invention is susceptible of some change and modification without material departure from the principles and spirit

thereof and for this reason I do not wish to 55 be understood as limiting myself to the precise arrangement and formation of the several parts herein shown in carrying out my invention in practice.

I claim:

A structure of the character described comprising a fixed or seat section, a back pivotally engaged therewith and provided with an extension adapted to underlie the fixed section, a swinging front pivotally engaged with the fixed section, a member supported for sliding movement by the fixed section and movable in the same horizontal plane in which the pivotal connection between the fixed section and the swinging front is positioned, and a rigid link operatively engaged with the extension of the hinged back and with the sliding member, whereby said sliding member will be projected beyond the fixed section to underlie the swinging front when the hinged back is lowered, and whereby said sliding member will be retracted when the hinged back is raised, said swinging front when in lowered position serving to lock the sliding member against outward movement and maintaining the back in upright position.

In testimony whereof I hereunto affix my signature in the presence of two witnesses.

TANDY B. THURMAN.
